UNITED STATES PATENT OFFICE.

JAMES W. LAWRENCE, OF NEW YORK, N. Y., ASSIGNOR TO HIMSELF, H. BREWSTER, AND JOHN W. BRITTON, OF SAME PLACE.

CONNECTING ELLIPTIC SPRINGS TO VEHICLES.

Specification of Letters Patent No. 26,461, dated December 13, 1859.

To all whom it may concern:

Be it known that I, JAMES W. LAWRENCE, of New York, county of New York and State of New York, have invented certain new and useful Improvements in the Construction of Light Road-Wagons; and I do hereby declare that the following is a full, clear, and exact description of the same, reference being made to the annexed drawing, 10 making a part of this specification, which is fully described herein.

In the construction of this class of vehicles a desired feature has been the attainment of the utmost degree of lightness without a sacrifice of the required amount of strength, and the various parts of this kind of wagon have been from time to time so much improved by inventive ability that while the weight has been within a few years reduced 20 to not more than half, the strength and durability have been greatly increased.

My improvement lies in the manner of affixing the elliptic spring, generally preferred, upon the back axletree, and of securing the parts in place. This has heretofore been usually accomplished by passing a strip of iron known as a "clip" over the spring, the lower ends of which strip are threaded and enter holes in a straight piece 30 placed up against the underside of the axle tree, and securing them there by nuts. To hold the parts properly together two of these, placed a few inches apart, and midway of the axletree have generally been employed, or three bolts have sometimes been 35 used, passing through the leaves of the

spring, the axle bed, and the iron axle-tree. These bolts weaken the axle bed and the axle at the point where the greatest strength is required.

In the annexed drawing the central portion of a back axletree is represented with the lower part of an elliptic spring secured to it by my improved clip, which is thus constructed: At (a) is seen the bent part of 40 the clip, and upon this is forged solid a plate (b) extending out on each side, as shown. The lower part of the clip (c) is forged solid with the iron portion (d) of the axletree, and the threaded ends of (a) 45 are secured by the nuts (a'). In the ends of the plate (b) are small bolts the countersunk heads of which are seen at (b') by which it is secured to the leaves of the spring (c) and by which those are secured 50 to each other. The spring, the axle bed (f) 55 and the iron of the axle tree are held together without the possibility of their being displaced and thus another point is attained in the construction of these wagons where- 60 by their strength and lightness are increased.

I claim—

The manner of combining and securing the back axle and the elliptic spring, specifically as described herein.

In testimony whereof I have hereunto subscribed my name.

JAMES W. LAWRENCE.
